UNITED STATES PATENT OFFICE.

GEORGE B. LEWIS, OF SAN FRANCISCO, CALIFORNIA.

DESIGN FOR A SPOON, FORK, OR SIMILAR ARTICLE.

43,624.

Specification for Design.

Patented Feb. 25, 1913.

Application filed April 22, 1912. Serial No. 692,503. Term of patent 7 years.

To all whom it may concern:

Be it known that I, GEORGE B. LEWIS, a citizen of the United States, residing in the city and county of San Francisco and State of California, have invented a new, original, and ornamental Design for Spoons, Forks, or Similar Articles, of which the following is a specification, reference being had to the accompanying drawing, forming part thereof.

Figure 1 is a plan view of the obverse side of a spoon, fork or similar article con-

structed in accordance with my design. Fig. 2 is a sectional perspective view of the obverse side of the handle on the line X—X of Fig. 1.

I claim:

The ornamental design for a spoon, fork, or similar article, as shown.

GEORGE B. LEWIS.
